[57] CLAIM

The ornamental design for a modular record rack, substantially as shown.

DESCRIPTION

FIG. 1 is a front elevational view of a modular record rack showing my new design;
FIG. 2 is a side elevational view thereof;
FIG. 3 is a rear elevational view thereof;
FIG. 4 is a top plan view thereof;
FIG. 5 is a bottom plan view thereof; and
FIG. 6 is an isometric view thereof.
